PLATENLESS TYPEWRITER

Charles W. Dohn, Glendale, N. Y.

Application June 24, 1946, Serial No. 678,942

11 Claims. (Cl. 197—2)

1

My present invention relates to an improved platenless typewriter and more particularly to a typewriter designed to write or impress the type print upon paper or other material located under the machine. The typewriter of my invention does not require a platen roll and the machine is so constructed as to move relatively to the paper or other matter rather than have the paper move relative to the machine as is customary in the conventional machines. The machine may be modified so as to be used for writing upon vertically disposed material as well as horizontal as herein described and other and varied uses will be apparent.

According to my invention the machine is supported upon rollers spherical in shape, the rollers being journaled under the machine, and the movement of the type key moves the machine to the right over the paper while the line spacer moves the machine downward over the paper, and the line return moves the machine to the left over the paper stopping at a predetermined margin setting.

The machine of my invention consists in novel combinations and arrangements of parts as will hereinafter be more fully set forth and described.

In the drawings:

Figure 1 is a perspective view of the machine of my invention.

Figure 2 is a schematic view of the parts of the typewriter comprising my invention.

Figure 3 is an enlarged perspective view of the spherical rollers and the journals therefor.

Figure 4 is a detail view of the roller and ball bearing.

Figure 5 is a top plan view of the roller construction taken at line 5—5 of Figure 3.

Figure 6 is a detail view of the end of the spacer arm showing the detents engaging the notched wheel on the spacing shaft.

Figure 7 is a perspective view of the margin limiting and setting mechanism.

Figure 8 is a top plan view thereof.

Figure 9 is a detail view of the line spacing mechanism as related to the shaft operation.

Figure 10 is a vertical sectional view of the line spacing mechanism as related to the operating lever.

Figure 11 is a top plan view thereof.

Figure 12 is a vertical sectional view of the tension spring and the gears attached thereto for affording motion to the spacer shaft.

Referring now to the drawings in detail wherein the structure shown will be construed as exemplary rather than limiting I have illus-

2

trated a sheet of paper as 1, or other material upon which it is desired to write. The typewriter of my invention consists in a case 2 having ends 3 and carrying handles 4, and operating mechanism as hereinafter outlined.

The typewriter having the general appearance and operating structure of a conventional typewriter has keys 6 each having levers 8 operated thereby. A spacer key is shown at 10, a carriage release at 12, and a line lock as at 14.

A margin indicator is provided as at 16 and the margin release key is shown at 17. A carriage shift key is provided at 19 and the type levers 18 are seen rearward of the case 2. Spools 20 carry ribbon 22 through the ribbon carrier 24, and other conventional controls on the case include a back spacer key 26, a line spacer 28, a line space adjuster 30 and a line resetter 32.

The case 2 of the typewriter is provided with legs 34 and these legs are fashioned with depending prongs or claws 35. Ball bearings 36 are seated in the prongs or claws and bear against the exterior of the spherical typewriter bearings 37. These spherical bearings 37 may be of suitable material such as metal, wood or plastic, and are covered with a rubber cover 38 or other suitable or desirable material capable of frictional contact with the ball bearings and the surface of the paper or other work upon which the machine is operating.

Referring now to the schematic showing of Figure 2, and the accompanying detail views, the key 6 and the lever 8 therefor terminate in a vertical arm 39 pivoted as at 40 on the machine.

A lug 42 depends outwardly and downwardly from the vertical arm and is designed to engage the lever 44 which is pivoted on the machine as at 46 and is connected with the link 48, connecting the lever with the lug 50 on the type lever 18. The type levers 18 are mounted pivotally upon the type carrier 51. At the upper portion of the type lever 18 I have illustrated conventional type, upper at 54 and lower at 52, and it will be understood that the type levers and the type thereon are of normal or usual design. Thus depression of a key 6 will through the linkage and lever connections actuate the type lever connected with the depressed key to impress through the ribbon, the character upon the paper 1 therebelow.

Laterally carried by the machine and in the path of movement of the vertical arm 39 of the key lever 8 is the universal bar 56. The universal bar 56 under movement of the arm 39 moves backward against the tension of the spring

57 and the universal bar is fashioned with an extended arm 58 suitably secured thereto. Upon this arm 58 I have shown the spacer 60 having a fixed detent 62 and a pivoted detent 64 pivoted at 64a, and urged downwardly by spring 65 into engagement with the toothed wheel 66. As the universal bar is moved forwardly by the spring 67 upon release of a depressed key lever, the fixed detent is disengaged from the tooth of the wheel and the pivoted spring-pressed detent is engaged with the next succeeding tooth thereof to allow movement of the toothed wheel one notch peripherally.

The toothed wheel 66 is fixedly secured on the shaft 68 and near the end of the shaft I have mounted bearing disks 70 formed with circumferential concave surfaces 72 having a radius equal to the radius of the spherical rollers 37. The surfaces of these bearing disks are of a frictional material suitable to engage the surface of the sphere in non-slipping and positive engagement.

Also on this shaft 68 I employ a bevel gear 74 rotatable therewith and engaging a second bevel gear 76 on the shaft 78 which shaft carries a dial 80 indicating the margins within which it is desired to confine the typewritten matter on the paper 1.

A lug 82 and a cam lug 84 on the under side of the dial 80 provide limits for the movement of the machine and the limits may be set by movement of the left margin set 86 and the right margin set 88.

A gear 90 on the shaft 68 engages a gear 92 journaled with relation to the housing 96 on the shaft 98. A flat coil spring 100 is positioned within the housing and one end 101 engages the shaft 98 while the other end 102 is anchored on the housing.

This coil spring provides the power for the motion of the carriage and the machine and as the detent 62 moves out of engagement with the toothed wheel 66 on the shaft 68, the shaft is permitted to turn a distance equal to one notch by the tension of the spring 100. In other words, it is the release of the fixed detent 62 and the concomitant engagement of the stepping dog 64 with the wheel 66, that permits the shaft 68 to turn under the influence of the spring 100 until the stepping dog is finally arrested, with the inferior spring 65 fully compressed by the engagement of the upper edge of said dog with the member 80, Figure 6.

The line spacing mechanism for the typewriter of my invention is best seen in the schematic showing of Figure 2 and the related detail figures including Figures 9, 10, and 11.

In this structure I employ a shaft 110 having bearing disks thereon as 112 concave at 114 and similar to the disks 70 above described. These disks 112 are adapted to engage the spherical rollers 37 under control of the line spacing lever 28 as will be hereinafter described.

The shaft 110 and the disks 112 are maintained in contact with the bearings 37 by means of levers 116 and springs 118. On the shaft 110 is a ratchet wheel 120 and the detent 122 pressed by spring 123 prevents retrograde movement of the shaft. A dog 124 pivoted at 125 on the lever 130 confines the action of the pawl 126 and the pin 127. The pawl 126 is also pivoted on the lever 130 which lever is rotatably mounted on the shaft 110. The pawl 126 is designed to engage the teeth of the ratchet wheel 120 and to move the ratchet wheel and shaft a predetermined distance de- 75

pending upon the setting of the line space adjuster 30.

A link 132 is fashioned with a pin 133 and this link operably connects the lever 130 with the vertical shaft 136 by means of the shaft arm 134. The vertical shaft 136 is journaled in a bearing 138 on the frame of the machine and rotates therein.

Outwardly and upwardly extending prongs 140 on the shaft 136 are secured to a ring or disk 142 having an open center 144. A second separate vertical shaft 146 is journaled in the typewriter case and has a reduced end 148 to receive the end of the lever 28. A disk 150 on the lower end of the shaft 146 carries a dog 152 pivoted at 153 and spring-pressed as at 154 and said dog is engageable with a detent 156 on the ring 142. Thus as the lever 28 is moved clockwise, the disk 150 rotates within the ring 142 until the dog 152 engages the detent to rotate the ring and its shaft 136. Through the linkage the shaft 110 is rotated and the disks 112 engage the spherical bearings 37 to rotate them and thereby to move the machine the predetermined number of spaces downward. As the dog 152 continues its swing after passing the detent, it reaches the abutment 158 fixed to the machine, and the continued pressure on the lever 28 moves the machine to the left to begin the next line.

From the above description of the related and associated parts and their operation it will be apparent that I have provided for the conventional machine, a structure whereby the paper remains stationary and the machine moves relative thereto, the movement of shaft 68 providing movement of the machine laterally to provide for the succeeding letter to be typed, and the shaft 110 provides for the movement longitudinally to carry the machine successively to the next line position and to the beginning of the next line to be typed.

By the use of the machine of my invention, there is no limit to the size or character of the material upon which the matter is to be typed, and the machine may be placed upon any flat surface and will write thereon. The non-conventional movements of the machine are accomplished by conventional operations so that no skill other than normal typing skill is required.

Having thus fully described my invention what I claim as new and desire to secure by Letters Patent is:

1. In a typewriter movable over the material receiving the writing, the combination with supporting spheres for the typewriter, of means for revolving the spheres to move the typewriter laterally and longitudinally under actuation of the keys and line spacing lever, respectively, of the typewriter.

2. In a typewriter movable over the material receiving the writing, the combination with supporting spheres journaled in the typewriter, of disks engageable with the spheres to revolve the spheres and means for rotating the disks.

3. In a typewriter movable over the material receiving the writing, the combination with supporting spheres journaled in the typewriter, of disks engageable with the spheres to revolve the spheres, an axle for the disks, and means for rotating the axle.

4. In a typewriter movable over the material receiving the writing, the combination with supporting spheres journaled in the typewriter, of disks engageable with the spheres to revolve the

spheres, a spring-pressed axle for the disks, and means for rotating the axle.

5. In a typewriter movable over the material receiving the writing, the combination with supporting spheres journaled in the typewriter, of concave, frictional-surfaced disks engageable with the spheres, an axle for the disks, and means for rotating the axle.

6. In a typewriter movable over the material receiving the writing, the combination with supporting spheres journaled in the typewriter, of sphere engaging disks, an axle for the disks, a notched wheel on the axle rotatable therewith, a universal bar movable under actuation of a key, and means on the universal bar operable under movement of said bar to release the wheel and permit movement thereof to revolve the spheres.

7. In a typewriter movable over the material receiving the writing, the combination with supporting spheres journaled in the typewriter, of sphere engaging disks, a spring rotated axle for the disks, a notched wheel on the axle rotatable therewith, a universal bar movable under actuation of a key, and a spring returned detent on the bar operable under movement of said bar to release the wheel and permit the axle to be rotated by its spring to revolve the spheres.

8. In a typewriter movable over the material receiving the writing, the combination with supporting spheres journaled in the typewriter, of sphere engaging disks, an axle for the disks, a lever having an arcuate swing, and means operable by the lever during the first portion of its swing for rotating the axle to move the typewriter longitudinally, the second portion of the swing of said lever causing the means to abut the typewriter frame to move the typewriter laterally.

9. In a typewriter movable over the material receiving the writing, the combination with supporting spheres journaled in the typewriter, of rotatable means engageable with said spheres for revolving the spheres to move the typewriter longitudinally, means for actuating said rotatable means including a vertically disposed shaft having a horizontally positioned ring on the upper end thereof, means connecting the vertically disposed shaft to the rotatable means, an upper shaft aligned with the said vertically disposed

shaft and having a disk thereon positioned to coact with the ring of the vertically disposed shaft, interengaging means on said ring and disk, and a hand lever carried by the said upper shaft.

5. 10. In a typewriter movable over the material receiving the writing, the combination with supporting spheres journaled in the typewriter, of disks engageable with the spheres, a horizontally disposed shaft on which the sphere engaging disks are mounted, means for actuating said horizontally disposed shaft including a vertically disposed shaft having a horizontally positioned ring on the upper end thereof, means operatively connecting the vertically disposed shaft to the horizontally disposed shaft, an upper shaft aligned with the said vertically disposed shaft and having a disk thereon positioned to coact with the ring of the vertically disposed shaft, interengaging means on said ring and disk, and a hand lever carried by the said upper shaft.

10. 11. In a typewriter movable over the material receiving the writing, the combination with supporting spheres journaled in the typewriter, of disks engageable with the spheres, an axle for the disks, an operating lever, a shaft operably connected with said axle and a ring on the shaft, an aligned shaft connected with the operating lever and having a disk, a spring-pressed dog on the disk, a detent on the ring adapted to be engaged by the dog during a partial movement of the lever to revolve the spheres to move the typewriter longitudinally, and a typewriter supported abutment engageable by the dog during the further movement of the lever, to move the typewriter laterally.
